UNITED STATES PATENT OFFICE.

EDWIN H. EHRMAN, OF CHICAGO, ILLINOIS, ASSIGNOR TO THE WALKER & EHRMAN MANUFACTURING COMPANY, OF SAME PLACE.

SEAT-POST CLAMP.

SPECIFICATION forming part of Letters Patent No. 619,469, dated February 14, 1899.

Application filed December 23, 1897. Serial No. 663,166. (No model.)

To all whom it may concern:

Be it known that I, EDWIN H. EHRMAN, a citizen of the United States, residing in Chicago, in the county of Cook and State of Illinois, have invented a new and useful Improvement in Seat-Post Clamps, of which the following is a specification.

This invention relates to an improved construction of seat-post clamp; and it consists of the combination, with the seat-post and the frame-tube receiving it, of an inner thimble contractible at both ends and made abruptly tapering at its top and gently tapering at its bottom, an outer thimble expansible at its lower end and made tapering internally to correspond with the taper of the lower end of the inner thimble and threaded at its upper end and also provided with a shoulder to engage the upper end of the frame-tube, and a screw-cap covering both thimbles and engaging the thread of the outer one and acting to force the inner one downward, and thus to expand the lower end of the outer thimble and at the same time contract the upper end of the outer thimble, so as to firmly hold the post at both the upper and lower ends of the clamp.

The nature of this improvement will be better understood from the accompanying drawings, in which—

Figure 1 is a side elevation of the device as applied to a bicycle. Fig. 2 is an enlarged vertical section of the clamp, showing the post in position therein. Figs. 3 and 4 are elevations of the inner and outer thimbles, respectively. Fig. 5 is a section on the line 5 5 of Fig. 2. Figs. 6 and 7 illustrate modifications.

In said drawings, A represents the seat-post, and B the frame-tube in which it is inserted.

C is the inner thimble and is slit throughout its length, as seen at C', and is also provided with other slits C², extending upward from its bottom for only a portion of its length. At its upper end it is abruptly tapering, as seen at C³, and at its lower end it is made gently tapering in a reverse direction from its upper taper, as seen at C⁴. The outer thimble is shown at D, and it is also slit from the bottom upward for a portion of its length, as at D'. At its upper end it is threaded, as at D²,

and adjacent to this threaded portion is an annular shoulder D³, which rests upon the upper end of the frame-tube B. Interiorly at its lower end the thimble D is made tapering in the reverse direction from the taper C⁴ of the inner thimble. This will be understood from Fig. 2, where the taper is clearly shown at D⁴. It will be seen from this construction that the inner thimble is contractible at both ends and that the outer thimble is expansible at its lower end; also, that when the inner thimble is forced downward it will expand the outer thimble against the inner surface of the frame-tube. The cap is shown at E. It is threaded interiorly to engage the thread D² of the outer thimble and also provided with a beveled interior surface E', corresponding to the bevel C³ of the inner thimble. With this construction of the parts of the clamp it will be seen that when they are assembled, as clearly indicated at Fig. 2, the cap is adapted to force the inner thimble downward, so as to cause the expansion of the lower end of the outer thimble against the inner surface of the frame-tube B. At the same time that this expansion of the outer thimble occurs a reflex action is caused upon the inner thimble, which contracts the lower end of that thimble against the seat-post, so the post is held very firmly in the plane of the lower ends of the thimbles. When the downward movement of the inner thimble stops by reason of the compression thus caused at its lower end, the screw-cap will then act to contract the upper end of the inner thimble against the post, so as to hold the latter in the plane of the upper ends of the thimbles. While the post is thus clamped by both ends of the inner thimble both the clamp and post are supported by the shoulder D³, and the friction by the outer thimble upon the inner surface of the tube is sufficient to hold the parts stationary in the tube.

It will be noticed that while the taper at the lower ends of the thimbles is slight it is not so much so as to prevent the withdrawal of the post by an upward pull thereon after the cap is unscrewed, and it is rendered unnecessary to attach the cap to the inner thimble so it may actuate the latter in both directions; also, that the inner thimble is cylin-

drical between its conical or tapering portions, and that such cylindrical portion enables the separation of the more active clamping portions of the thimble for any desired 5 distance, so that the post can be afforded a wide bearing.

Instead of holding the outer thimble in the frame-tube by friction in the manner described said thimble may be made non-expansible and be brazed or otherwise secured to the tube, or the outer thimble may be wholly dispensed with, and the inner taper D^4 thereof may be made integral with the frame member. These modifications are shown at 15 Figs. 6 and 7.

While I have shown and described the invention as applied to a seat-post, it will be understood that it may be used in securing handle-bars to the steering-posts of bicycles, 20 and, in fact, it may be used whenever two parts, one of which is provided with a cylindrical socket into which the other enters, are to be detachably united.

I claim—

25 1. The combination in a seat-post clamp of a contractible and longitudinally-movable thimble encircling the post and made reversely tapering at its ends, the taper at one

end being abrupt and that at the other end being gentle, an outer thimble tapered interiorly to correspond to the gently-tapered end of the inner thimble and acting to compress that end when the inner thimble is moved longitudinally, and a cap acting on the abruptly-tapered end and causing both the contraction 35 of that end and the longitudinal movement, substantially as specified.

2. The combination in a clamp-joint for adjustably securing together two parts, one of which enters within the other, the combination of a contractible and longitudinally-movable inner thimble abruptly tapering at one end and gently tapering at the other end, an outer expansible thimble tapering interiorly to correspond with the gentle taper of 45 the inner thimble, and a cap threaded on the outer thimble and acting on the abruptly-tapered end of the inner thimble and causing first a longitudinal movement of said inner thimble and a consequent compression of its 50 lower end, and then a compression of its upper end, substantially as specified.

EDWIN H. EHRMAN.
